UNITED STATES PATENT OFFICE

133,418

DESIGN FOR A PREFABRICATED HOUSE

Victor C. Norquist, Kansas City, Mo., assignor to
The Dymaxion Company, Inc., Wilmington,
Del., a corporation of Delaware

Application May 24, 1941, Serial No. 101,131

Term of patent 14 years

To all whom it may concern:

Be it known that I, Victor C. Norquist, a citizen of the United States, residing at Kansas City, in the county of Jackson and State of Missouri, have invented a new, original, and ornamental Design for a Prefabricated House, of which the following is a specification, reference being had to the accompanying drawing, forming a part thereof.

In the drawing,

Figure 1 is a front elevational view of a prefabricated house embodying my new design.

Figure 2 is a top plan view of said prefabricated house.

I claim:

The ornamental design for a prefabricated house, as shown.

VICTOR C. NORQUIST.
